UNITED STATES PATENT OFFICE.

ELIAS BERLOW, OF EAST ORANGE, NEW JERSEY.

RADIO APPARATUS.

Application filed March 2, 1925. Serial No. 12,487.

This invention relates generally to radio apparatus, having more particular reference to radio sets, the invention having for an object the provision of a novel and improved set of this sort, in which the wiring is carried in a separate compartment from the various instruments, to be concealed from view, and in which the various instruments may be readily exposed to view. 5 For further comprehension of the invention, and of the objects and advantages thereof, reference will be had to the following description and accompanying drawing, and to the appended claims in which the various novel features of the invention are more particularly set forth. 10

Fig. 1 of the drawing is a face view of my improved radio set.

Fig. 2 is a rear view thereof.

Fig. 3 is an underside plan view, the bottom element in the base being removed.

Fig. 4 is a transverse sectional view taken on the line 4—4 of Fig. 1.

Fig. 5 is a transverse sectional view showing a modification.

Referring now to the drawing, the reference numeral 10 indicates the base of the set which consists of a hollow rectangular frame-like member which may be formed with a laterally projected base flange 11 as shown. Upon its top side this member is chambered or recessed around the opening therein as at 12 to receive the edges of a baseboard 14 that supports certain of the instruments, and which is supported on the base 10. I have shown at 16 a series of sockets to receive the tubes 17. These sockets 16 extend downward through the base board instead of resting directly on the top thereof as is customary, and are formed with lugs or ears 18 that rest on the said baseboard and receive the screws that secure the sockets to the baseboard. 30

Mounted on the baseboard 14, adjacent the front edge thereof, is a panel 20 which supports the usual variable condensers, rheostats, couplers and the like, the condensers being indicated at 21, the couplers at 22, and the rheostats at 23, the adjusting knobs 50 of the condensers 21' being shown at and mounted on the front of the panel, while the knobs for controlling the rheostats are shown at 23 on the panel. The baseboard and panel are preferably made from bakelite, hard rubber, or any other suitable material.

Upon its rear marginal portion the baseboard is provided with the necessary binding posts and jacks indicated generally at 25 whereby connections are made to the antenna, ground, batteries, and ear phones or loud speaker. The electrical connections between the different instruments of the set are all made under the baseboard 14, the wires from the condensers and couplers 60 passing directly downward through openings formed in the said baseboard, while the sockets 16 have their terminals below the baseboard. In addition, the fixed condensers, transformers and the like are preferably mounted under the baseboard. A partition member or false bottom 28 may extend across the base 10 under the base board 14 and at a sufficient distance from the latter to accommodate the wiring and other 70 elements. The inside wiring under the baseboard is indicated generally at 29.

To complete the cabinet housing the instruments I may employ panels 30 of glass, wood or other material, the panels being 80 here shown as of glass and secured together by angle brackets such as 31. The improved radio set thus constructed is characterized by ornamental design and attractive appearance, all the unsightly parts being concealed 85 beneath the baseboard 14.

In Fig. 5 I have shown a modification in which the cabinet may be tilted back on the base 10 and the cover 30' of the cabinet thrown open by single operation. As here 90 shown the cover is hinged to the rear wall 30a of the cabinet as at 32. Fixed in each end of the base is a transverse plate 34 having a horizontal slot 35 formed at one end with a curved extension 36, this extension 95 being substantially concentric with the rear edge of the baseboard 14. The latter is provided with a pair of downwardly projecting brackets such as 37 having pins such as 38 on their lower ends that engage in the slots 35. 100 36. The cover 30' is adapted to be lifted by means of a pair of thrust rods such as 40 located one in each corner of the cabinet and extending at their lower ends through the baseboard. These rods are urged upwardly 105 by means of expansion springs such as 41 coiled therearound and are retained in normal position by means of levers such as 42 fulcrumed between their ends to brackets such as 43 on the underside of the baseboard. 110 These levers each having one end projecting through slotted apertures such as 44 in the

rods 40 and having outturned lugs 45 on their other ends that rest on shelves or flanges such as 46 on the plates 34.

When access to the various parts is desired the cabinet is tilted upward on the rear edge of the baseboard, and then moved slightly forward to engage the pins 38 in the slots 36. As the cabinet is swung upward the levers 42 are freed from the flanges 46 and the springs 41 act to tilt the cover upward.

Having thus described my invention, what I claim as new and desire to protect by Letters Patent of the United States is as follows:

1. A radio set comprising a cabinet including a panel and baseboard, a hollow base on which said cabinet rests, radio instruments mounted on said baseboard and panel, electrical wiring connections for said instruments extending under said baseboard, connection elements for external instruments on said baseboard exterior to said cabinet, and having their wiring extending under the said baseboard, said cabinet having a hinged top

and being arranged to be tilted upward on said base to expose the said wiring, and means whereby tilting movement of the said cabinet lifts the said cover.

2. A radio set comprising a cabinet including a panel and baseboard, a hollow base on which said cabinet rests, radio instruments mounted on said baseboard and panel, electrical wiring connections for said instruments extending under said baseboard, connection elements for external instruments on said baseboard exterior to said cabinet, and having their wiring extending under the said baseboard, said cabinet having a hinged top and being arranged to be tilted upward on said base to expose the said wiring, and means whereby tilting movement of the said cabinet lifts the said cover, including thrust rods engaged with said cover, springs urging said thrust rods upward, and levers engaged with said thrust rods normally retaining the same in inoperative position.

In testimony whereof I have affixed my signature.

ELIAS BERLOW.
